UNITED STATES PATENT OFFICE.

ALAN MACKENZIE McNEILL AND WILLIAM JOHN ABBOTT, OF AUCKLAND, NEW
ZEALAND.

BINDER-CASE FOR DOCUMENT AND LIKE FILES.

1,397,645.

Specification of Letters Patent.

Patented Nov. 22, 1921.

Application filed October 25, 1920. Serial No. 419,277.

To all whom it may concern:

Be it known that we, ALAN MACKENZIE McNEILL and WILLIAM JOHN ABBOTT, subjects of the King of Great Britain, residing 5 at Auckland, in the Dominion of New Zealand, have invented new and useful Improvements in Binder-Cases for Document and like Files, of which the following is a specification.

10 This invention relates to the binder cases used in holding document, letter and like files during the period of their filling, in order to protect such files and to provide a holder therefor in which they are held in 15 positions such that the papers may be readily placed in their proper compartments or withdrawn therefrom at will.

The invention has been devised especially with the object of providing a binder case 20 adapted for use in conjunction with a file of book-like form, such as is described and covered by our co-pending application for patent Serial No. 419,278 of even date here-with, and consisting of leaves bound together 25 with expandable binding. This case is designed to hold such a file within it and to keep it in a flat position and also to securely hold the papers within the file in such a manner that they may be examined, whenever 30 desired, either as to the major portions of their surfaces, or as to the top right hand corners, or the bottom right hand corners, at will.

The invention consists in constructing the 35 binder case of skeleton book cover form, having top and bottom covers of approved stiff material and a back hinge connecting them together, of the necessary width to provide for the two covers remaining parallel 40 when the file within them is full to its greatest capacity. The said bottom cover is provided with means whereby the file laid thereon may be held firmly in position.

Combined with this bottom cover is a 45 band or strap of approved material and width that extends down from the upper to the lower edge of this cover and above the file secured thereon. This band is provided with a buckle fastening, by means of which 50 it may be drawn tight or loosened at will, and it is connected to the cover, at both of its ends, by special means designed to allow for it being moved laterally across the width of the cover either in a line parallel with

the side edges thereof, or to occupy diagonal 55 positions at either angles from the upper to the lower corners. These means form the principal feature of the present invention and will be hereinafter fully described in relation to the accompanying sheet of drawings in which—

Figure 1 is a plan view of the complete case in the open position and with a file in position therein.

Fig. 2 is a lower edge view thereof, but 65 with the case closed.

Fig. 3 is a cross sectional elevation of the means for attaching one end of the band or strap to the corresponding edge of the case cover.

Figs. 4 and 5 are detail views, respectively of portions of the case bottom cover and the file, showing suitable means whereby the file may be secured to the said cover.

The case is formed with a stiff bottom 75 cover A and top cover B connected together by the stiff back C hinge connected to each of such covers and of the necessary width to provide for the file's capacity. It therefore, in effect, forms a skeleton book so that 80 a file of book form, such as the alphabetical index form of file D shown in the drawings may be laid with its bottom cover upon the inside face of the bottom cover A of the binder case and when held therein may be 85 opened and closed as a book. In placing documents in the file therefor, the case may be held with its back C downward on the lap and its bottom outward, when the different divisions of the file may be easily seen 90 and the leaves of the file parted at the required places to receive the documents.

Any approved means for attaching the file D to the cover A may be employed, providing they are of such a nature as to permit 95 of the file being readily removed, when full, and a fresh one placed in its position, as a re-fill. The means for this purpose shown in the drawings, consist in spring dome button fastenings secured upon the inner surface of the bottom cover A near its back edge, and upon the under surface of the bottom cover of the file D, as shown in Figs. 4 and 5 where the male member of such fastening is shown as E and is fixed to the cover 100 and the female member is shown at F and is fixed to the file.

Secured along the inner surface of the bot-

tom cover A at each of its upper and lower edges, is a metallic slide guide G that extends across practically the full width of such cover. The said guide is formed with 5 overhanging upper and lower edges g. A slide plate H is provided and is placed within the guide so as to extend beneath the edges g in such a manner as to allow the plate to slide freely along the guide, but to 10 prevent it lifting out. The slide plate is provided with lugs h projecting upward between the edges g and in these lugs a bent wire loop J is pivoted. This loop is made of approved length and its outer end is made 15 broad enough to allow of the broad band or strap K being passed around it and maintained in a flat condition. The band or strap K thus provided is passed through and around both loops J so that it extends down 20 across the full height of the cover, and its two ends are brought together and secured by a buckle K' or like fastening. The band therefore extends over the top of the file D and serves, when drawn tight, to hold the 25 papers placed in such file, securely in position, the band being loosened and pushed right to the inner edge of the file, when papers are being filed, by pushing the slide plates H in along the respective guide G. 30 Or, by positioning the band at about half way across the width of the file, while keeping it taut, the outer edges of the file may be turned up to allow of any particular paper 35 being located. Or, again, by moving one slide plate H inward along its guide and the other outward in its guide, the band may be arranged to extend diagonally across the file, as shown by the dotted lines in Fig. 1, in which position, the freed outer corners of 40 the file leaves and the papers therein may be turned over, in order to inspect the dates or

the signatures of the papers, as the case may be.

To facilitate this positioning of the band at the diagonal angles referred to, while 45 maintaining its flat condition, each slide plate H is made with its edges that engages the guide sides, slightly rounded, as shown in Figs. 1 and 3 so that it may swivel in the guide and thus accommodate the outer broad end of the loop J to the different angles assumed by the band. The band therefore remains flat in all positions, while by making the loops J of approved length they may be caused to raise the band level to approximately 50 the height of the filled file as shown in Fig. 2.

We claim:—

1. A binder case for document and like files made of book cover form, having means 60 for the attachment of a file to the inside of its bottom cover and having slide guides fixed to extend laterally one across each of the upper and lower edges of the said bottom cover, a slide plate mounted in each of 65 such guides and adapted to move to and fro along it, a loop pivoted to each of such plates, and a band or strap passed through both of such loops and having means for securing its ends together. 70

2. A binder case for document and like files constructed as described in claim 1, and in which each slide plate is so formed that it may swivel within its guide. 75

In testimony whereof we have signed our names to this specification in the presence of two subscribing witnesses.

ALAN MACKENZIE McNEILL.

WILLIAM JOHN ABBOTT.
